[57] CLAIM

The ornamental design for a packing insert for a suitcase, as shown and described.

DESCRIPTION

FIG. 1 is a perspective view of a packing insert for a suitcase showing my new design;

FIG. 2 is a perspective view thereof in the folded condition; and

FIG. 3 is a left side elevational view, the right side elevational view being a mirror image thereof and the bottom surface is plain and unornamented.

FIG. 1

FIG. 3
